(57) **CLAIM**

The ornamental design for an extruded channel, as shown and described.

DESCRIPTION

FIG. 1 is a front, right, top perspective view of an extruded channel;

FIG. 2 is a rear, right, bottom perspective view thereof;

FIG. 3 is a front view thereof;

FIG. 4 is a rear view thereof;

FIG. 5 is a right side thereof;

FIG. 6 is a left side thereof;

FIG. 7 is a top plan view thereof; and,

FIG. 8 is a bottom plan view thereof.

The extruded channel is shown with a symbolic break in its length. The appearance of any portion of the extruded channel between the break lines forms no part of the claimed design.

1 Claim, 5 Drawing Sheets*FIG. 1*

FIG. 2

FIG. 5

FIG. 6

FIG. 7

FIG. 8
